UNITED STATES PATENT OFFICE.

JOHN F. OHMER AND FREDERICK L. OHMER, OF DAYTON, OHIO; SAID FREDERICK L. OHMER ASSIGNOR TO SAID JOHN F. OHMER.

AUTOMOBILE-SERVICE RECORDER.

1,360,567.

Specification of Letters Patent. Patented Nov. 30, 1920.

Application filed June 12, 1919. Serial No. 303,691.

To all whom it may concern:

Be it known that we, JOHN F. OHMER and FREDERICK L. OHMER, citizens of the United States, residing at Dayton, in the county of 5 Montgomery and State of Ohio, have invented certain new and useful Improvements in Automobile-Service Recorders, of which the following is a specification.

This invention relates to new and useful 10 improvements in automobile truck service recorders and is an improvement of the mechanism shown and described in our Patent, No. 1,258,803, granted to us March 12th, 1918.

15 The main object of the invention is to provide a service recording machine which enables the ascertainment of full data or information incidental to the expense, earnings and time involved in operating auto 20 trucks and similar motor vehicles.

A further object of the invention is to provide means in a service recorder whereby the operations of the entire vehicle, including the recording mechanism, are wholly 25 under the control of clock or time mechanism. That is to say, the clock mechanism must be maintained in a running condition in order that the vehicle shall be kept in an operative condition.

30 To this end the machine is of a character which will give a printed record of the driver's control of the truck or vehicle, the time at which the truck begins and ends its useful service, and the time at which various 35 operations are performed in connection with the operation of the truck, the number of miles the truck has traveled during any one trip, the number of trips, the number of the particular truck, the amount of gasolene and 40 oil placed in the machine and the time at which they were so placed and by whom they were placed in the machine, the amount of time required in loading and unloading, and the amount of idle time consumed by the 45 truck, as well as any other data that may be serviceable in enabling the owner to be informed of the service as well as the expense and time attending its performance. These 50 and other objects will be more fully indicated in the specification to follow and pointed out in the claims.

Preceding a more particular description of the said invention, reference is now made in general terms to the accompanying drawings, of which Figure 1 is a front elevation

of the mechanism of the machine with the casing shown in section.

Fig. 2 is an end elevation of the mechanism at the left end of the machine, looking at Fig. 1.

Fig. 3 is a similar elevation of the right end of the machine.

Fig. 4 is a section on the line 4—4 of Fig. 1.

Fig. 5 is a section approximately on the 65 line 5—5 of Fig. 4.

Fig. 6 is a detail view of the flexible connections for the mileage and time mechanisms.

Fig. 7 is a perspective view of the identification key.

Fig. 8 is a view of the clock-setting key.

Fig. 9 is a plan view of the right end of the printing mechanism, and Fig. 10 is a view of a printed statement or record such 75 as the machine is capable of furnishing at any time.

Referring more particularly to the accompanying drawings, 1— represents a rear plate which supports frame plates 2—3— 80 and 4, upon which plates the mechanism, with the exception of the printing device, is mounted. The said rear plate 1— also supports a casing 5— which incloses the mechanism of the machine.

Mounted within the plates 2—3 and 4 is a shaft 6— upon which is mounted a plurality of printing wheels the location of said shaft being best shown in Figs. 2— and 4—. At the extreme left, as seen from 90 Figs. 1 and 5, is a series of type wheels 7 which together with their accompanying transfer wheels 8— mounted on a shaft 9—, constitute and operate as a counter. Mounted between the first and second wheels 95 from the right, is a plate 10— (Fig. 5) supported by the shaft 6— and provided with a projection 11— adapted to print a period and permitting the counter to indicate tenths of miles as will be seen from 100 Fig. 10—. The mileage counter is actuated from a wheel of the truck, and the right hand printing wheel 7 thereof is provided with a gear 12— in mesh with a duplex gear 13— mounted on a shaft 105 14— as will be seen from Figs. 1 and 2—. The gear 13— is, in turn, in mesh with a gear 15— mounted on a shaft 16— supported in the plates 2— 3— and 4—.

The shaft —16— is provided with a worm gear —17— in mesh with the worm —18— mounted on a vertical shaft —19— which is journaled in bearings —20— on the rear of the plate —1—.

The lower end of the shaft —19— is adapted to be connected in any well known manner with one of the wheels of the truck, and the timing of the above specified gear is such that the right hand wheel of the mileage counter will make one tenth of a revolution for each tenth of a mile of travel. To the right of the mileage counter are three type wheels —21—22— and —23—. The wheel —21— is adapted to print indications of miscellaneous data such for example, "time on," "time off," "load," "unload," "idle," "trip," "repairs," "oil," "gas," etc., and other suitable information pertaining to the operation of the truck. The wheels —22— and —23— are adapted to print numbers as will be seen from Fig. 10, and indicate the quantity, weight or volume of the item printed by wheels —21—22— and —23— are set by means of gears —24— and telescopic shaft —25— which extend out through the casing —5—. On their outer ends the shafts —25— are provided with setting drums —26—27— and —28— the peripheries of which are provided with visual indications corresponding to the printing indications on the wheels —21—22— and —23—. The drums —26—27— and —28— are set through the aid of a shield —29— which indicates what type are in printing position. To permit the numbers on the wheels —26— and —27— to be read in proper sequence, and to eliminate an obverse order due to the pressure of the telescopic shafts, the drums —26— and —27— are nested, and the drum —27— is provided with openings —30— through which the numbers on the drum —26— are visible. To the right of the gears —21—22— and —23— are arranged type wheels —31—32— and —33— adapted to print the date. These type wheels are manually set by means of gears —34—, telescopic shafts —35— and drums —36— which are identical with the gears, shafts and drums above referred to.

To the right of the wheels —31—32— and —33— are type wheels —37— which are adapted to print the time. The wheels —37— actuate as a counter and are provided with transfer wheels —38—. The unit wheel of the said counter is provided with a gear —39— in mesh with a duplex gear —40— mounted on a shaft —41—. The gear —40— is provided with a pinion —42— in mesh with a drive gear —43— of a clock —44— and by means of which the time counter is actuated. The time counter is provided with a visual indicator as follows: The gear —39— is in mesh with an idler —45— mounted on a shaft —46— and in turn in

mesh with a gear —47— mounted on a shaft —48— which carries a worm —49—. The worm —49— is in mesh with a gear —50— mounted on a plate —51— on the outside of the casing —5—. An hour hand —53— is also provided which is actuated through reducing gears —54—. The hands —52— and —53— move over a clock dial (not shown). The wheels —37— and the hands —52— and —53— are set by a key —55— shown in Fig. 8. The said key —55— is provided with a pinion —56— on its end and the said key is adapted to be inserted into the machine through an opening —57— adjacent to the gear —40—. By placing the pinion —56— in mesh with the gear —40— the wheels —37— and the hands —52— and —53— may be rotated. To the right of the time wheels —37— is a stationary type —58— adapted to print the machine number, or the number of the truck as the case may be. The type —58— is supported by a key-housing —59— attached to the plate —4—. The said housing —59— is adapted to receive a printing identification key —60— which is insertible through the outside of the casing and is provided with a type —61— adapted to print the number of the driver to identify him, or the inspector, or any other authorized person.

All of the printing type above described are mounted in alignment, and mounted below the same is a platen —62—, see Figs. —4— and —9—. The platen —62— is provided with arms —63— pivoted at —64— to end plates —65— and —66—. The said end plates are rigidly connected by a curved plate —67— and are pivoted at —68— to the rear plate —1— of the machine. Passing over the said platen —62— is a paper strip —69— which unwinds from a roll —70— mounted on a spindle —71— supported in the side plates —65— and —66—. To permit of the insertion of the roll of paper —70—, the printing mechanism is lowered on its pivots —68— after having opened the door —92— which forms the bottom of the casing. The printing mechanism is held in an upper or printing position by hooks —93— depending from a rock shaft —94— journaled in the plates —2— and —4—. The hooks —93— are adapted to engage pins —95— extending from the end plates —65— and —66—. The said hooks are further held in engagement with the pins —95— by a spring —96— mounted on the shaft —94—.

To secure an impression on the paper from the type, the platen —62— is elevated by a cam —72— having shaft extensions —73— and —74— journaled in the end plates —65— and —66—. The said shaft extension —74— is provided with a square end to receive a sliding sleeve —75— which extends out of the casing. On its outer end the sleeve —75— is provided with a knob

—76— by means of which the cam —72— can be rotated and the said platen thereby elevated. To lock the said cam in a normal position, the sleeve —75— is provided with 5 a flange —77— having a recess —78— adapted to receive a pin —79— mounted on a member —80— attached to the end plate —66—. By pressing inwardly on the knob —76— against the tension of a spring —81—, the flange —77— is moved out of the path of the pin —79— which in turn permits the said knob and the cam —72— to be rotated. Retrograde movement of the knob —76— and the cam —72— is prevented by 10 15 20 25 30 35 40 45 50 55 60 65 70 75 80 85 90 95 100 105 110 115 120 125 130 a ratchet —90— mounted on the shaft extension —73— and in operative relation with a spring controlled pawl —91—. After the knob and cam have made one revolution, the recess —78— receives the pin —79— which indicates that the printing operation is completed. After passing over the platen —62— the paper strip —69— passes between feed rollers —82— mounted on shafts —83— and —84—. The said feed rolls —82— are pressed together by spring-controlled levers —89— which bear down on the ends of the upper shaft —83—. On its right end the shaft —84— freely carries a Swiss gear —85— adapted to be engaged by an intermediate gear —86— on the shaft extension —74—. The shaft —84— is driven from the Swiss gear —85— through ratchet mechanism —87—.

The said ratchet mechanism permits the feed rollers to be manually rotated, when inserting the paper, by a disk —88— on the left end of the shaft —84—. When the platen —62— is actuated by rotating the knob —76— the feed rollers will be partially rotated thereby permitting the various impressions to appear consecutively as seen in Fig. 10—. The paper feeding operation takes place at the end of the printing operation.

Previous to the taking of an impression the type are inked by a roller —97— mounted on a spindle —98— and drawn upwardly by springs —99—. The ends of the spindle —98— ride in slots —100— in levers —101— pivoted to the plates 2 and 4. The levers —101— and the ink roller —97— carried thereby are moved to and held in an outer position by springs —102—. The lower ends of the levers —101— are provided with slots —103— adapted to receive pins —104—. The pin —104— at the right is mounted on a crank —105— while the pin at the left is mounted on a disk —106—. The crank —105— and disk —106— are mounted on the shaft extensions —74— and —73—.

During the actuation of the printing mechanism and before the platen begins to ascend, the pins —104— pick up the levers —101— and carry the inking roll —97—

under the type. After the type have been inked the said pins release the cranks and the roller snaps back under the influence of the springs —102—.

To align the type on the mileage and time counters 7 and 37, the right hand wheel on the primarily actuated wheels thereof are each provided with a star wheel —107— having the same number of teeth as there are characters on the wheels. The star 75 wheels —107— are adapted to be engaged by pawls —108— mounted on a rock shaft —109— journaled in the plates 2—3— and 4. The shaft —109— is provided with a spring —110— which normally maintains 80 the pawls —108— out of the path of the star wheels —107—. The left end of the shaft —109— is provided with an arm —111— having an anti-friction roller —112— adapted to normally lie in a cam recess —113— in 85 the disk —106— of the printing mechanism. When the printing mechanism is actuated the shaft —109— is rocked which operation places the pawls —108— in engagement with the star wheels —107— thereby aligning the 90 primary actuated type wheels.

To permit of the aligning movement of the type wheels without disturbing the actuating means therefor, the transmission gears 13 and 40 are made duplex, one portion of the 95 gear is provided, as is shown in Fig. 6, with a hub —123— which fits into a boss —124— on the other portion of the gear. The hub —123— has a recess —125— which receives a spring —126— lying in a pocket —127— 100 and attached to the boss —124—. This arrangement permits of a slight relative movement between the two portions of the gears 13 and 40.

The remaining type wheels of the counters 105 are in turn aligned from the primary wheels by their transfer wheels in a well known manner. The pawls —108— are held in engagement with the star wheel during the entire operation of the printing mechanism. 110

The manually set type wheels may be aligned by any suitable well known means such as spring-pressed rollers which ride over the teeth of the setting gears.

To compel the taking of an initial impression before the truck can be operated, means are provided to close the ignition circuit of the engine after each alternate operation of the printing mechanism. Mounted in the rear plate 1 is a casing —114— in which are 115 mounted two conductors —115—. The said conductors —115— are provided with contact points —116— adapted to be placed in engagement by a plunger —117—. The plunger —117— is provided with an anti-friction roller —118— which rides on a cam —119—. The cam —119— is pivoted at —120— to the member —80—. The cam —119— is also attached to a gear —121— in mesh with a pinion —122— mounted on the 125 130

shaft extension —74—. The ratio of the gears —121— and —122— is two to one. The printing mechanism must therefore be actuated twice to make and break the ignition circuit at the contact points —116—. In the position the parts are shown in the drawings, the first impression has been made and the ignition circuit is closed.

To compel a certain sequence of operations, the following devices are provided. See Fig. 3. The key —60— is provided with a cam face —128— adapted, when the key is inserted in the machine, to rock a lever —129— and to unlock the printing mechanism by moving a projection —130— out of a recess —134— in a disk —132a— attached to the gear —121—. When the key is withdrawn, a spring —131— places the projection in the said recess thereby locking the printing mechanism. As the ignition circuit cannot be closed until the printing mechanism is actuated and as the printing mechanism cannot be actuated until a key is inserted, the lever —129— therefore compels for the first operation, the insertion of the key.

After the printing mechanism has been actuated for the first time, and for each alternate time thereafter, the key —60— is locked in position by a lever —132— the free end of which is adapted to enter a recess —133— in the said key. This lever —132— is controlled by the spring —131— and a pin —135— mounted in the cam —119—. It will be seen that the levers —129— and —132— compel two operations of the printing mechanism intermediate of the insertion and extraction of the key, but permitting subsequent actuations of the printing mechanism without withdrawing the key.

To prevent the truck being operated when the clock —44— is not wound sufficiently to drive the time printer, the winding shaft —136— thereof, as is shown in Fig. 3, is provided with an intermittent gear —137— in operative relation with a Swiss gear —138— pivoted at —139—. The gear —138— is provided with a disk —140— having a block of insulation —141— which is adapted to be engaged by brushes —142— mounted on the casing —114— and connected into the ignition circuit. When the brushes —142— are in contact with the disk, —140— the circuit is closed and the truck may be operated, but when in engagement with the insulation the circuit is open. As shown in Fig. 3, the clock is unwound and the block —141— will be moved away from the brushes when the clock is wound and will move toward the brushes during the operation of the clock.

Mode of operation.

After the clock is wound, the date wheels 65 —31—, —32— and —33— are properly set,

and the paper strip —69— is in place, the operator inserts his key —60— which in the present instance, as shown by the record in Fig. 10, is that of the inspector. The insertion of the key rocks the lever —129—, 70 moves the projection —130— out of the recess —134— of the disk —132a— thereby unlocking the printing mechanism. Before actuating the printing mechanism, the operator sets the wheels —21—, —22—, and 75 —23—, to print any necessary data. The operator then actuates the printing mechanism by pushing on the knob —76—, thereby moving the flange —77— out of the path of the pin —79— and gives the knob a complete 80 revolution. The initial movement of the printing mechanism locks the key in position as the pin —135— releases the lever —132— thereby permitting the spring 85 —131— to move the free end of the lever —132— into the recess —133— of the key —60—. At the same time the mileage and 90 time counters —7— and —37— are aligned through the instrumentality of the star wheels —107—, levers —108—, shaft —109—, arm —111— and disk —106—. During the subsequent operation of the printing mechanism, the inking roll —97— is moved over the face of the type in printing position, through the agency of the pins 95 —104— and levers —101—. The subsequent movement of the printing mechanism elevates the platen —62— by the cam —72— and presses the paper strip —63— against the type thereby securing an impression. 100 The continued movement of the printing mechanism feeds the paper strip forward as the intermittent gear —86— will partially rotate the Swiss gear —85— which drives the feed rollers —82—. The final movement 105 of the printing mechanism of the first and alternate operations thereafter, closes the ignition circuit at the points —116— through the means of the plunger —117— and —119— and gears —121— and —122—. 110 The motor is then in a condition to be tested by the inspector in the present instance, or the truck to be operated when the same cycle of operations has taken place, upon the subsequent insertion of the driver's key. To 115 permit of the withdrawal of the key the inspector, or driver, on subsequent operations, must take a second impression. During this impression he prints the amount of oil supplied, he having in the present instance, 120 printed the amount of gasoline on the first impression. On the initial movement of the second printing operation, the contacts —116— are broken, and at the end of the second and subsequent alternate operations, 125 the pin —135— moves the lever —132— out of the recess —133— of the key, thereby allowing said key to be withdrawn. The same operations take place when the driver 130 has taken charge of the truck and he also,

upon taking each impression, manipulates the data wheels —21—, —22—, and —23— to print any pertinent information.

At the time of taking each impression, the mileage the truck has subsequently traveled and since the previous impression was taken, and the time at which the impression is taken will be indicated thereon. This gives an infallible record of the service of the 10 truck, as the means for operating the mileage and time counters are out of the control of the drivers entirely.

While we have described our invention with some particularity we do not desire to 15 be limited to details as these may be varied without departing from the underlying principles of the invention.

Having described our invention we claim:

1. In a service recorder for motor vehicles, a clock-driven time counter, a mileage counter driven from a wheel of said vehicle, printing mechanism for taking impressions from said counters showing the distance traveled by said vehicle and the time consumed, and means actuated from said printing mechanism, including a plunger adapted to control the ignition circuit of said vehicle, and whereby said ignition circuit is closed when an impression is taken from 30 said time and mileage counters.

2. In a service recorder for motor vehicles, a clock-driven time counter, a mileage counter driven from a wheel of said vehicle, printing mechanism adapted to 35 simultaneously interrupt the ignition circuit of said vehicle and take an impression from said time and mileage counters, and means actuated by said printing mechanism and including a plunger engaging the switch 40 of said ignition circuit.

3. In a service recorder for motor vehicles, a clock-driven time counter, a mileage counter driven from a wheel of said vehicle, shiftable type for printing miscellaneous 45 data, printing mechanism for taking impressions from said counters and type, a cam and plunger actuated by said printing mechanism and controlling the switch of the ignition circuit of said vehicle, whereby the 50 ignition circuit is closed when an impression is taken from said counters and said type.

4. In a service recorder for motor vehicles, a clock-driven time counter, a mileage 55 counter driven from a rotating part of the vehicle, said time and mileage counters being flexibly connected to their respective driving means, printing mechanism for taking an impression from said counters, a cam 60 actuated by said printing mechanism, and a plunger actuated by said cam and engaging the switch of the ignition circuit of said vehicle, whereby said circuit is closed when said printing mechanism is operated to take

an impression from said time and mileage 65 counters.

5. In a serving recorder for motor driven vehicles, a time printing counter, a mileage counter driven from a rotating part of said vehicle, clock mechanism controlling said 70 time printing counter, and a switch connected to said clock mechanism, said switch being opened when the clock runs down whereby the ignition circuit of said vehicle is interrupted. 75

6. In a service recorder for motor vehicles, a time counter, a mileage counter driven from a rotating part of the vehicle, clock mechanism connected with said time counter, the winding mechanism thereof being adapted 80 to control the ignition circuit of the vehicle thereby rendering said vehicle operative or inoperative.

7. In a service recorder for motor vehicles, a time counter, printing devices for 85 taking impressions from said counter, clock mechanism connected with said time counter, said clock mechanism being also connected into the ignition circuit of the vehicle and arranged to interrupt said circuit when the 90 clock spring is unwound, whereby the vehicle is rendered inoperative until said clock spring is rewound.

8. In a service recorder for motor vehicles, a time counter, a mileage counter, 95 and clock mechanism controlling said time counter and connected with the switch of the ignition circuit of the vehicle, whereby the said time counter is operative while the clock mechanism is in action, and is rendered inoperative when the clock mechanism stops. 100

9. In a machine of the character specified, a time counter, clock mechanism controlling said time counter, a mileage counter driven 105 from a rotating part of a vehicle, impression devices adapted to take records from said counters of the time and mileage service of the vehicle, the clock mechanism being connected into the ignition circuit of 110 said vehicle whereby the vehicle is rendered operative or inoperative.

10. In a machine of the character specified, a time counter, clock mechanism controlling said time counter and the ignition 115 circuit of the vehicle, a mileage counter adapted to record the distance traveled by said vehicle when the clock is running, an identification device, and impression devices 120 cooperating with said counters and identification device in furnishing records therefrom indicating the service of said vehicle and the identity of the driver.

11. In a machine of the character specified, a time counter, a mileage counter 125 driven from a rotating part of a vehicle, a clock connected to said time counter and to the ignition circuit of the vehicle, said ig-

nition circuit being maintained closed while the clock is running whereby the mileage counter is rendered operative during such time, and impression devices for taking 5 records from said counters showing the mileage and time for any given period.

12. In a machine of the character described, a clock mechanism, an ignition circuit including a source of electrical energy, 10 said clock mechanism being connected into

said circuit and arranged to break said circuit when the clock mechanism stops, whereby the vehicle is rendered inoperative while the clock mechanism is in a stopped condition.

15 In testimony whereof we affix our signatures.

JOHN F. OHMER.
FREDERICK L. OHMER.
